WILBUR MORTON WISE, OF MANILA, PHILIPPINE ISLANDS.

TRACK-SHIFTER.

1,285,872.

Specification of Letters Patent.

Patented Nov. 26, 1918.

Application filed February 15, 1918. Serial No. 217,351.

To all whom it may concern:

Be it known that I, WILBUR MORTON WISE, a citizen of the United States, and a resident of Manila, Philippine Islands, have 5 invented a new and Improved Track-Shifter, of which the following is a full, clear, and exact description.

This invention relates to means for use in setting and readjusting tracks, and particularly what may be termed a track shifting device, and has for an object the provision of an improved arrangement whereby entire track or independent rails may be shifted quickly and easily without interrupting the traffic passing thereover.

Another object in view is to provide an improved, quickly adjustable gripping structure for rails capable of use in connection with an ordinary jack for acting on the 20 rails and causing the longitudinal movement thereof for resetting or shifting the position thereof to a new or desired position.

A still further object in view is the method of utilizing the jack and gripping 25 members for shifting tracks or rails without disturbing the traffic passing thereover.

In the accompanying drawing:

Figure 1 is a side view of adjacent ends 30 of rails and part of a roadbed together with an embodiment of the invention applied to the rails.

Fig. 2 is an end view of one of the clamps shown in Fig. 1 together with a part of a rail and part of a tie.

Fig. 3 is a top plan view of a number 35 of rails in correct position.

Fig. 4 is a top plan view of a number of rails shifted by creeping to an incorrect position, an embodiment of the invention 40 being shown associated therewith.

Fig. 5 is a side view of adjacent rail ends together with a filling member or temporary section positioned therebetween.

Fig. 6 is a perspective view of a slightly 45 modified form of wedge or key to that shown in Fig. 2.

Fig. 7 is a detail, fragmentary, sectional view through Fig. 2 on line 7—7.

It has been found by experience that rails 50 on double track railways move longitudinally or creep to a considerable extent as

the trains always move the same way, and consequently the action of the driving wheels of the engine tends to produce a movement of the rails. This creeping is 55 objectionable because the different rails creep continually and consequently the track becomes twisted, and in some instances the securing bolts on the fish-plates are sheared off, so that unless moved back to 60 their proper position accidents occur. To pull the spikes and move back the different rails to their proper position involves a considerable expense and also necessitates a considerable disturbance of the traffic, as a large 65 section usually is shifted at one time. Even where small sections are shifted the rails must be loosened to such an extent as to be dangerous for the passage of a train thereover. Various methods have been hereto- 70 fore used for shifting the rails, the most common one being the loosening of the joints, pulling the spikes in a single rail length and then inserting a wedge between the rails so as to crowd the loosened rail 75 back to its former position. Where the shifting of a rail is a very short distance, as for instance one inch, this method may be satisfactory, but where it is several inches or a foot, this method is more or less ob- 80 jectionable, by reason of the length of time required to accomplish the result desired and the expense involved. In the accom- 85 panying drawing a structure is shown adapted to move any rail, or number of rails, without interfering with the usual traffic passing over the rails. In some instances it is possible, by the structure shown in the drawing, to shift a small section, or a complete track, or shift a switch. 90

Referring to the accompanying drawing by numerals, 1 and 2 indicate the adjacent ends of rails of a railway, rail 1 being fastened rigidly in position by the usual spikes, while rail 2 is shown loose and shifted to 95 its original position. The idea is to loosen one rail, as for instance rail 2, while leaving rail 1 fastened in position, said loosening action being the drawing of the spikes for a short distance, as shown in Fig. 2. When 100 the spikes are drawn a short distance they will hold the rail in place sufficiently for

allowing a train to pass thereover if the fish-plates have been placed in position. To shift the rail as shown in Fig. 1 clamping members 3 and 4 are clamped to the respective rails while they are adjacent and then the jack 5 is placed therebetween and operated so as to push the loosened rail longitudinally. Clamps 3 and 4 are identical and are constructed as shown in Fig. 2, from which it will be seen that these clamps are provided with clamping plates 6 and 7 formed at their lower end so as to exactly fit the ball of the rail while the upper end is provided with a contact portion 8. The parts are so constructed as to leave an opening 9 whereby the bolt 10 passing through apertures in the plates 6 and 7 will cause a pressure at portion 8 and cause the lower end of the plate to grip tightly the ball of the rail. Bolt 10 is provided with a slot 11 for accommodating a key 12 which key is interposed between plate 6 and the washer 13. A nut 14 is mounted on the threaded end of the bolt and is tightened by a suitable wrench so that the parts will grip the rail as shown in Fig. 2. In case it should be desired to quickly remove the clamp nut 14 is given a short unscrewing movement and key 12 is then removed. This will provide ample space for movement of the plates 6 and 7 so that they may be disconnected from the rail. This quick detaching feature is desirable as when shifting the tracks in constant use the entire structure can be applied and removed quickly so as not to molest traffic. In case the bolt having the slot 11 is not convenient, or is not desired for any reason, a U-shaped structure 15 may be used, said U-shaped structure straddling the bolt instead of passing through the slot. Either structure will allow the device to be applied or removed by a very small movement of nut 14.

When the track is first laid the rails are arranged as shown in Fig. 3 with a small expansion space 16 provided therebetween. These rails are of course connected together by suitable fish-plates and are connected with the cross ties by suitable spikes now in common use. In case the rails shown in Fig. 3 use a single track with trains running both directions the creeping action would be balanced by trains going in the opposite direction and consequently the rails would remain usually in the position shown in Fig. 3. However, in parts of the country where there is a large amount of traffic two sets of tracks, or more, are provided so that the tracks will eventually assume the position shown in Fig. 4, though originally as shown in Fig. 5. In Fig. 4 it will be seen that a large opening 17 is found at one part of the track, and a small opening 18 at another part. The opening 18 is near a switch or other structure where a large number of

spikes are provided and other means are used which will prevent longitudinal movement of the rails. When the rails are positioned as shown in Fig. 4 it is necessary to move them back to their former position, 70 or the continued use would cause the tracks to buckle and to shear the bolts in the fish-plates. By using the construction shown in Figs. 1 and 2 one of the rails may be shifted or a number at a given time. For instance, 75 the bolts in the fish-plates at openings 17, 19, and 20 may be loosened and the spikes on rails 21 and 22 may be slightly turned and a shifting device 23, similar to that shown in Fig. 1 applied at the joint 20. A 80 wedge or plug of the proper length may be positioned in the opening 19 so that when the jack 5 is operated rail 22 will move the proper distance longitudinally toward opening 17 and then both the rails 21 and 22 will 85 move until the proper opening has been provided at 17. This will leave an extra wide opening at 20 which may be filled by shifting the other rails in the track singly or a number at one time as just set forth. 90 This method of shifting the rails will not injure the track nor the rails, as there is no pounding action on the abutting ends of the rails or no bruising of said rails by wedges acting thereon for spreading the 95 same. The arrangement of the clamps 3 and 4 are such that they will move the rails longitudinally without lifting the rails or without having a tendency to force the other rails downwardly as in the case of a wedge. 100 In case there should be a large opening between adjacent rails, as would be provided when the device 23 shown in Fig. 4 had moved the rails 21 and 22, a filling plug or section 24 could be inserted and held in 105 place by the usual fish-plate 25 for the passage of a train. The lengths of these sections 24 may be varied as may be required, preferably the sections are of a proper length for receiving two of the bolts of the 110 fish-plate where the fish-plate is provided with four bolts. If the fish-plate should be provided with more bolts the same section could be used for sections having three or more bolts to be utilized. It will of course 115 be evident that the lower portion or jaws 6' and 7' as well as the entire plates 6 and 7 are made sufficiently heavy and massive to withstand the strain applied thereto and to provide an ample gripping surface for engaging the rails. 120

What I claim is:

1. A rail shifter comprising a pair of clamping members, each of said clamping members comprising a pair of plates having 125 at one end jaws with sockets adapted to fit over the ball of the rail, and a fulcrumed projection at the other end, a bolt extending through said plates for clamping the plates to said rail, means for tightening said bolts, 130

and a spreading member associated with said clamps for giving movement to one of the rails engaged by said clamps.

2. A rail shifter comprising a spreading member and a pair of clamps, each of said clamps comprising a pair of gripping members for engaging the rail, a bolt extending through said gripping members for clamp-

ing said gripping members in position, and a U-shaped key member interposed between **10** the nut of said bolt and said gripping members whereby a small turn of the nut will permit the removal of the key member and a loosening of the gripping members.

WILBUR MORTON WISE.
